CLAIM

The ornamental design for a modular block system, as shown and described.

DESCRIPTION

FIG. 1 is a perspective view of a first modular block of the modular block system;

FIG. 2 is a top view of the first modular block of the modular block system;

FIG. 3 is a front elevation view of the first modular block of the modular block system;

FIG. 4 is a bottom view of the first modular block of the modular block system;

FIG. 5 is a rear elevation view of the first modular block of the modular block system;

FIG. 6 is a side elevation view of the first modular block of the modular block system, as viewed from the left in FIG. 1;

FIG. 7 is a side elevation view of the first modular block of the modular block system, as viewed from the right in FIG. 1;

FIG. 8 is a perspective view of a second modular block of the modular block system;

FIG. 9 is a top view of the second modular block of the modular block system;

FIG. 10 is a front elevation view of the second modular block of the modular block system;

FIG. 11 is a bottom view of the second modular block of the modular block system;

FIG. 12 is a rear elevation view of the second modular block of the modular block system;

FIG. 13 is a side elevation view of the second modular block of the modular block system, as viewed from the left in FIG. 8;

FIG. 14 is a side elevation view of the second modular block of the modular block system, as viewed from the right in FIG. 8;

FIG. 15 is a perspective of a third modular block of the modular block system;

FIG. 16 is a top view of the third modular block of the modular block system;

FIG. 17 is a front elevation view of the third modular block of the modular block system;

FIG. 18 is a bottom view of the third modular block of the modular block system;

FIG. 19 is a rear elevation view of the third modular block of the modular block system;

FIG. 20 is a side elevation view of the third modular block of the modular block system, as viewed from the left in FIG. 15;

FIG. 21 is a side elevation view of the third modular block of the modular block system, as viewed from the right in FIG. 15;

FIG. 22 is a perspective view of a fourth modular block of the modular block system;

FIG. 23 is a top view of the fourth modular block of the modular block system;

FIG. 24 is a front elevation view of the fourth modular block of the modular block system;

FIG. 25 is a bottom view of the fourth modular block of the modular block system;

FIG. 26 is a rear elevation view of the fourth modular block of the modular block system;

FIG. 27 is a side elevation view of the fourth modular block of the modular block system, as viewed from the left in FIG. 22;

FIG. 28 is a side elevation view of the fourth modular block of the modular block system, as viewed from the right in FIGS. 22; and,

FIG. 29 is a perspective view of the first, second, third, and fourth modular blocks of the modular block system set in a pattern.

The broken lines in the drawing views are included for the purpose of illustrating a portion of the modular block system that forms no part of the claimed design.
